UNITED STATES PATENT OFFICE.

CHARLES F. CHAPMAN, OF NEWARK, NEW JERSEY.

PACKAGE-SEALING MACHINE.

1,140,574.

Specification of Letters Patent. Patented May 25, 1915.

Application filed November 15, 1912. Serial No. 731,480.

To all whom it may concern:

Be it known that I, CHARLES F. CHAPMAN, a citizen of the United States, residing at Newark, in the county of Essex and State of New Jersey, have invented certain Improvements in Package-Sealing Machines, of which the following is a specification.

This invention relates to the closing and sealing of the ends of cartons and similar packages, such as are used at the present time for containing cereals and a great variety of other goods, either the bottom of the package before filling the same, or the top of the package to close and seal the package after filling.

The objects of the invention are to provide a carton-sealing machine, especially adapted to high speed operation; to provide, for this reason, such a machine in which the carton shall have a continuously forward movement during the successive operations upon it; to provide automatic means to perform the various operations and deliver the sealed carton; to obtain perfect synchronism of parts; to provide mechanisms to perform the necessary functions which will not be affected by slight variations in the size of the carton; to provide such mechanisms which will be readily adjustable for use with cartons of a different size; to provide such mechanisms that will not be injured or interrupted by an omission in the series of cartons being sealed; to provide such mechanisms which create no drag upon the flaps of the carton to twist the same out of proper position; to retain the last folded flap in position under pressure while the adhesive sets; to provide a receptacle for the adhesive which may be readily removed for cleaning or other purposes and may be accurately replaced without difficulty; to provide such means and mechanisms which are readily applicable to an endless conveyer of any ordinary and well-known type; to secure simplicity of construction and operation, and to obtain other advantages and results as may be brought out in the following description.

In the accompanying drawings, in which like numerals of reference indicate the same parts throughout the several views; Figure 1 is a side elevation of an endless chain carton-sealing machine embodying my invention; Fig. 2 is a plan of the same; Fig. 3 is a plan of one of the carton-carrying de-

vices or pockets, on larger scale; Fig. 4 is an elevation of the same viewed from the side of Fig. 3 away from the observer; Fig. 5 is an elevation of the sweep and the plow constituting the first and second folders, a carton being shown dotted in its correct position relative thereto, and the driving sprocket on the sweep being omitted for greater clearness; Fig. 6 is an elevation of said sweep looking at the same from the right hand side of Fig. 5; Fig. 7 is a plan view of the plow with its supporting bracket; Fig. 8 is a transverse section through the upper portion of the machine showing the adhesive receptacle and a carton-carrier both in elevation but each having parts sectioned to disclose details of construction; Fig. 9 is a side elevation of the adhesive receptacle with portions broken away for greater clearness; Fig. 10 is a view of the third folder as seen in Fig. 1, but on larger scale; Fig. 11 is a plan of the same; Fig. 12 is a longitudinal section through the same; Fig. 13 is a section on line A—A of Fig. 12 looking in the direction of the arrows; Fig. 14 is a transverse section through the upper portion of the machine showing the can for causing the fourth folder to close the last flap; Fig. 15 is a similar section through the lower part of the machine showing the cam for releasing said fourth folder from the carton; Fig. 16 is an elevation of the same as viewed in Fig. 1, and Fig. 17 is a plan of said releasing cam on a smaller scale than in Fig. 16.

In the specific embodiment of the invention illustrated in said drawings, and particularly Figs. 1 and 2 thereof, the reference numerals 1, 1 indicate the side pieces of the frame of my carton-sealing machine which supports between said side pieces and at its opposite ends pairs of sprocket wheels 2, 2 operatively connected by endless chains 4, 4. Said endless chains support between themselves at spaced intervals, carriers 5 which have each a pocket 6 adapted to receive a carton 7, and hold the same substantially perpendicular to the plane of the chains, all as clearly described in my former Patent No. 829,918 of September 4, 1906.

The carton 7 is inserted into the pocket 6 of a carrier 5 with the flaps to be sealed projecting upwardly therefrom, and the endless chains 4, 4, driven by any suitable power, carry the cartons on their upper run from the right-hand toward the left as viewed in

said Figs. 1 and 2 and indicated by arrows thereon. For convenience in referring to the flaps, the transverse one which is at the rear as the carton moves will be designated 5 as the first flap, and bears the reference numeral 8, and the flap parallel to or directly opposite the first flap 8 will be termed the second flap and is lettered 9 in the drawings; of the side flaps, which are parallel 10 to the direction of movement of the carton, the one nearest the observer viewing Figs. 1 and 2 will be referred to as the third flap 10, and the other flap 11 directly opposed thereto is to be designated as the fourth flap. 15 The second flap 9, as the carton is carried along, is engaged and slightly bent over by a sweep or first folder 12 which is swinging rearwardly upward to allow the first flap 8 to pass under and then swings for- 20 ward and downward after the passage of said first flap to close or fold it in the direction of and beneath the second flap 9. A plow or second folder 13 then engages the second flap 9 and closes it upon the first flap 25 into final position. Simultaneously the plow 13 spreads apart or bends outward the third and fourth flaps 10, 11, and holds them in such position until they are engaged by an adhesive applying roll 14. The carton passes 30 on, and beyond the said adhesive roll 14 the third flap is folded over by a third folder or brush 15 onto the already folded second flap. Directly following this last fold a clamp or fourth folder 16 closes the fourth 35 flap into place and remains upon it until the carton completes its circuit.

Describing more in detail these various mechanisms for folding the several flaps and directing particular attention first to the 40 sweep 12, reference is to be had at this time to Figs. 5 and 6 in which this device is shown in detail. A support or standard 17 is secured to the frame 1 of the machine by any suitable means such as the bolts 18, 18, 45 and provides upon itself a transverse bearing 19, above the path of the carton carriers. A shaft 20 free to rotate in said bearing but secured against longitudinal movement in any suitable and well-known manner, carries upon its one end a sprocket 21 for driving purposes, and upon its other end a crank 22. Pivotaly suspended from above said crank upon a pin 23 projecting parallel to the shaft 20 from a support 24 forming part 50 of the standard 17, is the body portion 25 of the sweep having longitudinally of itself a slot 26 receiving the pin 27 upon said crank 22. By this means I convert the rotary movement of the crank into an oscil- 55 latory or swinging movement of the sweep 25, it being noted that said sweep swings from the vertical position shown in full lines in Fig. 5 to the raised inclined position shown in dotted lines and then back 60 to said vertical position. Furthermore, 65

since the rotation of the crank 22, as viewed in Fig. 5 is in counter-clockwise direction, the sweep 25 is lowered quicker than it is raised, which secures results hereinafter more fully explained. However, it might be 70 desirable under certain conditions to give the sweep other motions, and I do not wish to be understood as limiting myself to the detail arrangement and operation specifically described. 75

For engaging the flap of the package or carton, I provide on the lower end of the said sweep body 25 an end piece 28 the lower engaging portion 29 of which is substantially perpendicular to the sweep. The forwardly directed extremity thereof, adapted to first strike the flap 8, is preferably curved or bent upward as at 30 to provide a smooth engaging surface to contact with the flap. It is furthermore desirable to have the end piece 28 adjustable up and down with respect to the carton so as to be adapted to sealing packages of any desired height, and for this purpose, I provide adjusting screws 31, 31 adapted to extend through a slot 32 in the end piece 28 to clamp the same to the sweep body. However, it will be appreciated that it is not necessary to have the adjustment specifically placed between the end piece 28 and the sweep body 22, as it might be between 95 two portions of the standard 17 or elsewhere and obtain practically the same result. 95

The plow or second folder 13 is shown in Fig. 5 in its proper relation to the sweep 12 and has a nose 33 which preferably is closely adjacent to the upturned lip 30 of the end piece of the sweep when said sweep hangs vertically downward. Referring to both Figs. 5 and 7, it will be seen that the plow comprises an outspread body 34 appropriately reinforced by a frame 35 with ribs 36 as may be found necessary for retaining its shape and giving it durability, said body tapering at its forward end to form the nose 33. In the preferred construction, the body of the plow is of a single piece of sheet metal having forward corner pieces bent upwardly inward to provide converging cheeks 37, 37, the extremities of said corner pieces being overlapped and secured by any suitable means such as the screw 38 projecting into the frame 34 of the plow. The nose 33 is also surfaced with an extension 39 of the sheet metal bent upwardly over the nose and secured by a screw 40. The plow 13 might 110 be made of an integral casting when so desired, instead of a frame and sheet metal body, as just described, but the sheet metal is preferable where it is desired to secure a smooth surface without having to machine 115 or polish a casting. 120

An extension 41 of the frame 35 projects upwardly near the forward end of the plow and a block 42 which is part of a bracket 43 bridging the frame 1, 1 of the machine is 130

adapted to fit against said extension 42, so that the plow can be supported thereon by a screw 44 put through said extension into the block. It will be evident that by slotting 5 said extension 41 of the plow for the insertion of the screw 44, adjustability of the plow can be readily secured in an up and down direction or toward and away from the carton.

10 Referring now to Figs. 8 and 9, it will be seen that spaced at a distance from the plow bracket 43 is a pair of standards or supports 45, 46 upon the side pieces 1, 1, of the machine frame, each of which has an upwardly open socket 47 for the reception 15 of a hub-like support 48 projecting laterally outward from an adhesive receptacle 49 whereby the end of said receptacle which is toward the direction of travel of the conveyer is supported. The other end of the receptacle 49 is provided with a shoulder 20 50 and rests upon the bracket 48.

In order to clamp the adhesive receptacle securely in place, I provide upon the standards 45, 46 arms 51 through which are 25 screwed clamping-studs 52, 52, having tapered inner ends adapted to wedge into correspondingly tapered recesses in the side walls 53 of the receptacle.

30 Rotatively mounted within the hub-like supports 48 above mentioned is an axle or shaft 54 having secured to itself and adapted to rotate therewith, the adhesive roll 14. The length of the roll 14 is preferably the 35 entire width of the interior of the adhesive receptacle 49, so as to form a front wall to the receptacle in connection with the sides 53, 53 thereof. Mounted on one end of said shaft 54, outside the standard 45, is a gear 40 55 meshing with a smaller gear 56 carried by a counter shaft 57 in suitable bearings 58, 58 of the standard 45, said countershaft 57 being directly below the shaft 54 of the roll. A sprocket 59 upon the countershaft 45 57 transmits its motion through said countershaft and gears 56, 56 to the adhesive roll, and rotates the same so that its bottom travels in the same direction, as the cartons are being carried by the conveyer. By the 60 construction of receptacle and roll just described it will readily be appreciated that when it becomes desirable to remove the receptacle, including the roll, for cleaning or other purposes, it is necessary simply to 65 unscrew the clamping studs 52, 52 and lift the receptacle so that the supports 48 are clear of the sockets 47 and the gears 55 and 56 disengage. I therefore avoid the necessity of removing the driving chain from 70 the sprocket 59, although if it were so desired the standards 46, 47 might be integrally or otherwise secured to the receptacle, and the sprocket placed directly on the shaft of the roll. This, of course, is 75 optional and is considered within the scope

of the invention. The bottom of said adhesive receptacle 49, is formed preferably by a leaf spring 60 secured imperviously to the lower end of the back wall 61 of the receptacle by any suitable means such as the 70 plurality of screws 62 shown in the drawings. Said leaf spring 60 extends from the back wall 61 to the adhesive roll 14 and bears against the same as it rotates, retaining the adhesive within the receptacle and 75 allowing only a film of it to remain on the roll. In order to regulate the thickness of this film by varying the tension of the leaf spring 60 against the roll 14, I provide a cam 63 extending longitudinally of the leaf spring 60 and intermediate of its lateral edges. This cam is operated by handles or knobs 64, one at each end of the cam, and to provide means for retaining the cam in any adjusted position, I insert spring 80 washers 65, 65 between the handles 64, 64 and the sides of the receptacle.

It will be noted that the plow folds the second flap 9 down into closed position upon the first flap 8, as indicated in dotted lines in 90 Fig. 5, and also bends back, into outwardly opened position, the side flaps 10 and 11, as shown in dotted lines in Fig. 8. The roll 14 is long enough to extend endwise over the said outstretched flaps 10, 11, and thus the 95 adhesive is applied to the inner surfaces of said outstretched flaps as well as to the top of the other folded flaps, as the carton passes under the roll 14.

A retaining guide or tracker 66 placed 100 slightly above the path of the carton, see Figs. 1 and 2, is adapted to prevent the opening up of the first and second flaps by their natural resiliency after leaving the adhesive roll until the third flap is sufficiently 105 bent over to prevent them from springing up. As the side flaps 10 and 11 clear the adhesive roll 14, it is found in practice that their natural resiliency is sufficient to cause them to return to an almost upright position, and it is from such substantially upright position that the folders next to be described are adapted to close said flaps to final position. It will be noted in passing, however, that the resiliency of the flaps requires that they be positively held down 110 when closed, and that before the folding or retaining means can be removed after closing any flap, the next flap must be sufficiently closed to prevent those previously closed 115 from springing open again.

The brush or third folder 15, shown in detail in Figs. 10 to 13 inclusive, is located at the left-hand side of the path of travel 120 of the carton, just beyond the guide or tracker 66, and has a horizontal arm 67 adapted to be passed over the flap 10 to close it and at the same time to travel in the direction of and at the same speed with the 125 carton so as to create no drag on the flap 130.

10 being folded. In order to effect this compound movement of the arm 67, I provide beneath the same a pair of parallel cranks 68, 68, revolving in a horizontal plane and 5 pivoted at their outer ends to said arm, one near the end of the arm away from the carton and the other at a point intermediate the ends of the arm. The arm is thus carried around in a circular orbit, although held 10 always substantially perpendicular to the path of travel of the carton, and the outer end of the arm overlies the carton only when the cranks 68, 68 are directed toward the carton and in alignment with the arm 67 or 15 nearly so. At this time the outer end of the arm 67 has a circular motion whose component perpendicular to the path of the carton serves to push the flap 10 down into closed position and then withdraw the arm, 20 the other component longitudinally of the path of the carton, carrying the arm along at substantially the same rate of travel as the carton. The flap 10 is thus closed very quickly, and during the remainder of the 25 revolution of the arm 67 the next succeeding carton is coming into position for its corresponding flap to be closed.

Evidently the rate of rotation of the parallel cranks 68, 68 may be proportioned 30 to their length so that the movement will be equal to any rate of travel of carton.

The cranks 68, 68 are mounted upon and project from vertical transmission shafts 69, 69 supported in the casing or body portion 70 of the folder. These transmission shafts have upon their lower ends beveled gears 71, 71 meshing respectively with beveled gears 72, 72 on a countershaft 73, and a driving shaft 74 parallel to and spaced 40 from said countershaft 73 has upon one end of itself a sprocket wheel 75 for driving and carries a gear 76 to mesh with a gear 77 secured to the countershaft 73.

Preferably, the length of the circular path 45 in which the carton-engaging end of the arm 68 travels is twice the distance between successive cartons, and in order to secure a speed of said engaging end equal to that of the carton when the two are in engagement, 50 I make the gears 76, 77 elliptic, as shown. Said elliptic gears are so arranged and adapted that when the end of the arm is over the carton it will be traveling at the same speed therewith and when at a diametrically opposite point of its orbit it will be traveling at four times the speed of the 55 carton, the average speed of the end of the arm being twice that of the carton since it has twice as far to go.

60 In order to render the folder adjustable to different widths of cartons, I construct a bracket 78 slidably adjustable upon the arm 68 by suitable means such as a bolt 79 in a slot 80 of the bracket 78. This bracket carries the means for engaging the carton flap

65 to close the same, and which means I have shown as a roller 81 although other engaging means might be employed, said roller being journaled horizontally and transversely of the arm 68, preferably at right angles 70 thereto, so that it always lies parallel to the path of travel of the carton. In order to secure a resilient downward pressure of the roller or other engaging means upon the flap, I prefer to mount it in a holder 82, having arms 83, 83 to receive the ends of the roller and opposite arms 84, 84 by which it is hinged to the bracket 78 to swing up and down. A stud 85 extends upward from said holder 82 loosely through an extension 86 of the bracket 78 and is threaded to receive above said extension adjusting nuts 87, 87, whereby the normal position of the holder 82 is adjusted vertically. A helical compression spring 89 upon the stud 85 between the 85 holder 82 and the extension 86 presses the holder yieldingly downward and tends to keep the roller in its said normal position.

A sprocket chain 90 connects the sprocket wheel 75 of this third folder or brush with 90 both the sprocket 59 of the adhesive roll and the sprocket 21 of the sweep and also connects them with a driving sprocket 91. This driving sprocket is upon a shaft 92 supported as by a bracket 93 on the frame 1 of 95 the machine, see Figs. 1 and 2, and connected to the main driving shaft 94 by means of a chain 95 and suitable sprockets therefor (not shown).

The carton carrier or pocket 5 is provided 100 with an upper bridge portion 96, see Figs. 3, 4 and 8, which extends transversely between the tracks 97, 97 along which the carton travels, said bridge preferably having at each end a plurality of rollers 98, 98 to engage said tracks 97 and hold the bridge in position. The carton is slipped into and held by the pocket 5 depending from said bridge portion 96, with its end having the flaps to be sealed projecting above said 110 bridge, and said projecting upper end is guided during the successive operations on its flaps by stationary guide rails 99, 99 adjustably supported on the frame 1 at the opposite sides of the carton and in sliding engagement therewith, see Figs. 8 and 2. The fourth folder or clamp 16 comprises a yoke 100 with arms 101, 101 pivoted to the front and rear edges of the bridge 96 just described intermediate of the ends thereof 115 which engage the tract 97, 97, said yoke being thus adapted to swing sidewise of the carton carrier and carrying between its arms adjacent to its closed end a clamping plate 102 adapted to engage the top of the carton 120 or be carried away from the same. The ends of said arms 101, 101 are preferably pivoted by screws 103, 103, and adjacent to said pivoted ends, the arms are offset inwardly as at 104, 104 so as to bring them closer to the 125

carton 7, and also to serve as a stop when the yoke swings to engage a carton, in case there should be no carton there to stop it, as will be understood from an inspection of Figs. 14 and 15. When the yoke swings in the opposite direction, or into idle position, it engages a rest 105 as shown clearly in Fig. 8 and elsewhere. To hold the said yoke at either limit of its swing, extension springs 106, 106 extend from the yoke downward at the front and rear ends of the bridge 96, and are secured to fixed supports 107. These springs are at their upper ends connected to the arms 101, 101 outside the same and above the points of pivoting of said arms, so that whichever way the yoke is tipped the said springs will draw it down to its limit of movement in that direction. The clamping plate 102 is pivoted between the arms 101, 20 101 of the yoke 100 by means of pintles 108, and said plate is held approximately in the proper angular relation to the yoke so that it will fall flat on the top of the carton by means of shoulders 109, 109 one adjacent to 25 each of said pintles and adapted to engage a corresponding adjacent shoulder 110 on the yoke. It will be understood that the clamping plate 102 provides a flat undersurface and that it has at its front edge or 30 the edge which first approaches the package a lip 111 curled upward so as to slide easily upon the flap 11 to be depressed, as shown in Fig. 14. Furthermore the clamping plate carries adjacent to said lip, fingers 112, 112 35 projecting forwardly from its engaging surface at opposite sides of the same and adapted to overlie the edges of the flap so as to hold the same against any edgewise displacement and cause it to be bent down 40 onto the top of the package in exact registration therewith. These fingers preferably have slotted portions overlying the top of the clamping plate and adjustably held by screws 113.

45 It will be understood that just as soon as the third folder or brush 15 has brought the third flap to closed position as shown in Fig. 12, the fourth folder operated to bend the fourth flap down upon the others and hold it 50 there; to accomplish this I provide upon the frame 1 of the machine, means for swinging the yoke 100 from the position shown in Fig. 8 to the position shown in Fig. 14 to bring the clamping plate 102 down upon the 55 top of the package, and these means will next be described. Projecting inward over the path of the carton carrier from the side piece of the frame opposite that upon which the third folder or brush 15 is mounted, as 60 shown in Fig. 2, is a stationary cam having a portion 114 whose guiding surface 115 inclines upwardly inward as shown in Figs. 2 and 14, so as to engage a projection 116 centrally disposed upon the closed end of the 65 yoke 100 and force said yoke upward from

its position as shown in Fig. 8 and swing it over upon the carton as illustrated by Fig. 14. Preferably the projection 116 is a roller to reduce friction. Obviously as soon as the yoke passes a vertical position it would be 70 closed violently down upon the carton or would slam the offsets 101, 101 against the bridge of an empty carton carrier, if no means were provided to prevent, and since such violent action might injure something, 75 I provide a second cam portion 117 whose inwardly and downwardly inclined cam surface 118 is adapted to guide the roller or projection 116 after it leaves the cam surface 115 and 80 ease the clamping plate 102 down onto the top of the carton, all as will be understood upon inspection of Figs. 1, 2 and 14.

It will be noted that the cam surfaces 115 and 118 lie in the surface of a cylinder 85 whose longitudinal axial line coincides with the line of pivoting of the yoke 100 upon the screws 103. After passing the said closing cam, the clamping plate 102 remains held firmly and forcibly against the top of 90 the carton by the spring 106 until the carton has nearly completed its circuit, so as to give the adhesive time to set sufficiently. Then the said roller or projection 116 of the 95 yoke 100 engages other means for swinging said yoke back into idle position, and preferably this means is located adjacent to the last end of the lower run of the conveyer, just before it passes around the sprocket wheel 2 at the right-hand end of the machine, as viewed in Fig. 1, so that after the clamping plate has been removed there is still time for the carton to drop out of its carrier by gravity. This releasing means preferably comprises a cam 119 mounted 100 upon the same side frame 1 of the machine as the closing cam already described, by means of suitable supports 120 adapted to hold it rigidly, and provides a cam surface 110 105 115 120 125 12b 130 1121 against which the roller or projection 116 of the yoke will engage as the carrier approaches. This engagement is clearly shown in Fig. 15 of the drawing, and the cam surface 121 curves upwardly outward in the surface of a cylinder whose axis coincides with the line of pivoting with the yoke, so that said yoke will be swung outwardly into idle position upon its rest 105. Preferably the cam surface 121 is one wall of a groove 122 whose other wall 123 catches the projection or roller 116 after it passes the vertical, said wall 123 being formed by a strip 124 secured to the edge of the cam 119 with its extremity 125 projecting therebeyond as a guide.

Obviously, other detail forms of cams, and supporting means therefor may be used, as desired, without departing from the spirit and scope of the invention, so long as they effect a closing and releasing of the clamp 130

as I have described. Also, other details of construction throughout the machine may be changed as suggested by mechanical skill to meet various conditions or facilitate manufacture.

It will be understood that there is one of the yokes 100, with its clamping plate 102 and other parts, on each carton carrier, which are actuated in turn by the closing and releasing cams on the frame of the machine as the carton carriers pass said cams. The folders for the other three flaps are all mounted on the frame, and engage the flaps as the carton passes. The third and fourth folders are, furthermore, automatically adjustable to slight variations in the height of the carton top such as are bound to exist even in cartons of the same size, and therefore a uniform pressure is secured on the third and fourth flaps which insures their smooth and even closing, without distortion by too great pressure or looseness because of too little.

It will be noted that the omission of a carton from any carrier will not interfere with the working of the machine, and I desire it understood that the flaps of cartons closed by my machine can vary, as in length or number, and still be properly closed, either with the machine as I have shown it or with one or more folders detached and the others re-located if necessary to preserve the sequence of operations.

Having thus described the invention, what I claim is:—

1. In a carton sealing machine, continuously moving means for conveying cartons, a sweep pivoted to swing longitudinally of the path thereof, and means for swinging said sweep to and from rearwardly retracted position and to and from forward vertical position with a motion on the forward stroke faster than that of the cartons and a motion on the rearward stroke slower than that of the cartons.

2. In a carton sealing machine, continuously moving means for conveying a carton, a sweep pivoted to swing longitudinally of the path thereof, and means for swinging said sweep to and from rearwardly retracted position and to and from forward vertical position with a faster motion on the forward stroke than on the rearward stroke.

3. In a carton sealing machine, means for conveying a carton, a support projecting beyond the path of the carton, a sweep pivoted on said support to swing longitudinally of the path of said carton, a rotary member journaled in said support, and means connecting said rotary member to said sweep to oscillate the same.

4. In a carton sealing machine, means for conveying a carton, a support projecting beyond the path of the carton, a slotted sweep pivoted on said support to swing lon-

gitudinally of the path of said carton, a crank mounted in said support intermediate the ends of the slot, and means for turning said crank.

5. In a carton sealing machine, means for conveying a carton, a plow adjacent the path of the carton comprising a skeleton frame and a sheet metal body bent over and secured to said frame, and means to adjust the plow to the path of the carton.

6. In a carton sealing machine, means for conveying a carton, and a plow adjacent the path of the carton comprising a frame having a longitudinal portion with a nose and an upward extension near said nose, and a sheet metal body on said frame having corners bent up and secured to said extension.

7. In a carton sealing machine, means for conveying a carton, and a plow adjacent the path of the carton comprising a frame having a longitudinal portion with a nose and an upward extension near said nose, and a sheet metal body on said frame having a portion bent up over said nose and upwardly bent adjacent lateral corners, all said bent-up portions being secured to said extension.

8. In a carton sealing machine, means for conveying a carton, and a plow adjacent the path of the carton comprising a frame having a longitudinal portion with a nose and an upward extension near said nose, and a sheet metal body on said frame having its forward lateral corners bent upward and inward to provide a tapered end.

9. In a carton sealing machine, means for conveying a carton, a support extending above the path of the carton transversely thereof, a plow adjacent the path of the carton having an extension adapted to engage said support and being adjustable with respect thereto, and means for fixing the plow in any position to which it is adjusted.

10. In a carton sealing machine, the combination of a track and means for conveying the carton along said track, of a removable adhesive reservoir extending across said track, an applying roll forming the front wall of said reservoir and adapted to engage the cartons, a scraper for said roll where it leaves the reservoir, means at the end of the roll for adjusting said scraper, and means for turning said roll.

11. In a carton sealing machine, the combination of a track and means for conveying the carton along said track, of an adhesive reservoir extending across said track, an applying roll forming the front wall of said reservoir and adapted to engage the cartons, a scraper for said roll where it leaves the reservoir, a transverse cam extending longitudinally beneath said scraper with finger pieces at its opposite ends, and means for turning said roll.

12. In a carton sealing machine, the combination with a track and means for conveying cartons along the same, of brackets on said track providing upwardly open seats, an adhesive reservoir having hubs adapted to engage said seats and a roller mounted in said hubs, gears on said roller and a bracket adapted to intermesh, and means for driving the gear on the bracket.
13. In a carton sealing machine, the combination with a track and means for conveying cartons along the same, of brackets on said track providing upwardly open seats, a support spaced from said brackets, an adhesive reservoir having hubs adapted to drop into said seats and means for engaging said support, a roller mounted in said hubs, gears on said roller and a bracket adapted to intermesh, and means for driving the gear on the bracket.
14. In a carton sealing machine, the combination with a track and means for conveying cartons along the same, of brackets on said track providing upwardly open seats and arms projecting therefrom, a reservoir having hubs adapted to drop into said seats and sockets in its sides, adjustable studs in said arms for engaging said sockets, gears on said roller and a bracket adapted to intermesh, and means for driving the gear on the bracket.
15. In a carton sealing machine, the combination with a track and means for conveying cartons along the same, of brackets on said track providing upwardly open seats and arms projecting therefrom, a support spaced from said brackets on the track, an adhesive reservoir having hubs adapted to rest in said seats and means for engaging the support, a roller mounted in said hubs and forming a wall of the reservoir, a leaf spring closing the bottom of the reservoir with a free edge engaging the roller, means for adjusting the pressure of said leaf spring against the roller, adjustable studs in the arms of the brackets adapted to engage the sides of the reservoir, a gear on the roller outside one of the brackets, a second gear on said bracket meshing with the first-mentioned gear, and means for driving the gear on the bracket.
16. In a carton sealing machine, means for conveying a carton continuously along a predetermined path, a brush projecting toward said path from one side thereof and adapted to fold the adjacent side flap of the carton, and means for imparting movement to said brush in a circular orbit having an arcuate portion of itself overlying said path longitudinally thereof, whereby the brush moves with the carton in the direction of movement thereof throughout engagement of the brush with the flap.
17. In a carton sealing machine, means for conveying a carton continuously along a predetermined path, a brush projecting toward said path from one side thereof and adapted to fold the adjacent side flap of the carton, and means for imparting a continuous curvilinear movement to said brush in an orbit parallel to the top of a carton held by said conveying means and having an arcuate portion of itself extending longitudinally of the path of the carton, whereby the brush moves with the carton in the direction of movement of the same throughout engagement of the brush with the flap.
18. In a carton sealing machine, means for conveying a carton continuously along a predetermined path, a brush at one side of said path substantially perpendicular thereto, and means for moving said brush in a curvilinear orbit parallel to the top of the carton so that it is always substantially perpendicular to the path of the carton and moves with the carton in the direction of movement of the same throughout engagement of the brush with the flap.
19. In a carton sealing machine, means for conveying a carton along a predetermined path, a brush projecting toward said path from one side thereof and adapted to fold the adjacent side flap of the carton, and means for imparting variable movement to said brush in an orbit parallel to the top of a carton held by said conveying means.
20. In a carton sealing machine, means for conveying a carton along a predetermined path, a brush projecting toward said path from one side thereof and adapted to fold the adjacent side flap of the carton, a pair of parallel cranks pivoted to said brush, and means for rotating said cranks.
21. In a carton sealing machine, means for conveying a carton along a predetermined path, a brush projecting toward said path from one side thereof and adapted to fold the adjacent side flap of the carton, parallel shafts, cranks on said shafts pivoted to said brush, and means for driving said shafts in the same direction.
22. In a carton sealing machine, means for conveying a carton along a predetermined path, a brush projecting toward said path from one side thereof and adapted to fold the adjacent side flap of the carton, a pair of parallel cranks pivoted to said brush, driving means, and intermeshing elliptical gears between said driving means and cranks.
23. In a carton sealing machine, means for conveying a carton along a predetermined path, a brush projecting toward said path from one side thereof and adapted to fold the adjacent side flap of the carton, parallel shafts, cranks on said shafts pivoted to said brush, driving means, and elliptical gearing between said driving means and shafts.
24. In a carton sealing machine, means for conveying a carton along a predetermined path, a brush projecting toward said path from one side thereof and adapted to fold the adjacent side flap of the carton, parallel shafts, cranks on said shafts pivoted to said brush, driving means, and elliptical gearing between said driving means and shafts.

- path; a brush projecting toward said path from one side thereof and adapted to fold the adjacent side flap of the carton, a pair of parallel shafts, cranks on said shafts pivoted to said brush, countershaft, beveled gears connecting said countershaft and parallel shafts, a driving shaft, and elliptical gears one on said driving shaft and the other on said countershaft.
- 10 25. In a carton sealing machine, means for conveying a carton along a predetermined path, a brush projecting toward said path from one side thereof and comprising aligned sections longitudinally adjustable with respect to each other, the outer section carrying means for engaging the adjacent flap of a carton, and means for moving said brush around an orbit to carry it toward and away from the carton.
- 15 26. In a carton sealing machine, means for conveying a carton along a predetermined path, a brush projecting toward said path from one side thereof and having at its end a member for engaging the adjacent side flap of a carton, said member being provided with means to adjust the same vertically to accommodate different heights of cartons and means to adjust said member horizontally to varied widths of cartons, and means 20 for moving said brush around an orbit to carry it toward and away from the carton.
- 20 27. In a carton sealing machine, means for conveying a carton along a predetermined path, an arm projecting toward said path from one side thereof, an adjustable bracket on said arm having an upper extension, a holder hinged to said bracket to swing up and down beneath said extension, means on 25 said holder for engaging the adjacent side flap of a carton, means limiting movement of said holder away from the extension, a spring between said holder and extension, and means for moving said arm around an orbit to carry it toward and away from the 30 said path of the carton.
- 25 28. In a carton sealing machine, means for conveying a carton along a predetermined path, an arm projecting toward said path from one side thereof, a bracket on the outer 35 end of said arm having an upper extension, a holder hinged to said bracket to swing up and down beneath said extension, a roller mounted in said holder for engaging the flap of a carton, means limiting movement of 40 said holder away from the extension, a spring between said holder and extension, and means for moving said arm in an orbit to carry it toward and away from the said 45 path of the carton.
- 50 29. In a carton sealing machine, the combination of a track, a carrier adapted to travel on said track and hold a carton with its top exposed, a yoke pivoted on said carrier, a clamping plate pivoted to said yoke for closing a flap of a carton in said carrier, means for resiliently holding the yoke at either end of its throw, and means on the track for swinging said yoke.
- 55 30. In a carton sealing machine, the combination of a track, a carrier adapted to travel on said track and hold a carton with its end exposed, a yoke pivoted on said carrier, means on said yoke for closing a flap against the end of the carton, a spring for holding said yoke at either end of its range of movement, and cams upon said track projecting into the path of said yoke, one adapted to swing it in one direction and the other to swing it in the opposite direction.
- 60 31. In a carton sealing machine, the combination of a track, a carrier adapted to travel on said track and hold a carton with its top exposed, a yoke having its arms pivoted to said carrier, a clamping plate pivotally carried between the arms of said yoke adjacent to its closed end, said yoke adapted to swing said clamping plate against the end of a carton in the carrier or away from said carton, and means upon the track for automatically swinging said yoke.
- 65 32. In a carton sealing machine, the combination of a track, a carrier adapted to travel on said track and hold a carton with its end exposed, a yoke pivoted on said carrier to swing transversely of the track, a clamping plate pivoted to said yoke to engage the top of a carton in the carrier when the yoke swings in one direction, means upon the track for automatically swinging said yoke, and means for holding it at either 70 end of its throw.
- 70 33. In a carton sealing machine, the combination of a track, a carrier adapted to travel on said track and hold a carton with its end exposed, a yoke pivoted on said carrier to swing at its closed end over the carton, means pivoted to said yoke for closing a flap of a carton in said carrier, means for resiliently holding the yoke at either end of its throw, and means on the track for swinging said yoke.
- 75 34. In a carton sealing machine, the combination of a track, a carrier adapted to travel on said track and hold a carton with its end exposed, a yoke pivoted at the ends of its arms to said carrier to swing transversely of the track, a plate pivoted in said yoke and adapted to engage the end of a carton as the yoke swings in one direction and to be removed therefrom as the yoke swings in the other direction, means for limiting movement of said plate with respect to the yoke, means for resiliently holding the yoke at either end of its throw, and means on the track for swinging said yoke.
- 80 35. In a carton sealing machine, the combination of a track, a carrier adapted to travel on said track and hold the carton with its end exposed, a yoke pivoted on said carrier to swing transversely of the track, a clamping plate pivoted to said yoke to 75

engage the end of a carton, adjustable fingers at the lateral edges of said clamping plate adapted to receive the carton between themselves, means for resiliently holding 5 the yoke at either end of its throw, and means on the track for swinging the said yoke.

36. In a carton sealing machine, the combination of a track, a carrier adapted to 10 travel on said track and hold the carton with its end exposed, a yoke pivoted on said carrier having stops on its arms adapted to engage the carrier in one direction of swinging, means on the yoke for engaging the 15 end of a carton, extension springs at opposite sides of the carrier adapted to hold the yoke against said carrier at both ends of its throw, and means on the track for engaging said yoke to swing the same.

37. In a carton sealing machine, the combination of a track, a carrier adapted to 20 travel on said track and hold the carton with its end exposed, a swinging member pivoted to said carrier, a clamping plate pivoted to said swinging member and adapted to engage the end of a carton, means for 25 resiliently holding said swinging member with said plate in engagement with a carton, and means on the track for automatically swinging said member as the carrier 30 travels along.

38. In a carton sealing machine, the combination of a track, a carrier adapted to travel on said track and hold a carton with its top exposed, a yoke pivoted on said carrier having means for engaging the end of a carton, and cams upon the track having surfaces to engage said yoke lying in the surface of a cylinder whose longitudinal axis coincides with the line of pivoting of 40 the yoke.

39. In a carton sealing machine, the combination of a track, a carrier adapted to travel on said track and hold a carton with its top exposed, a yoke pivoted on said carrier to swing transversely of the track, means on said yoke for engaging the end of a carton, and cams on said track each having a surface to engage said yoke on one side of its upright position perpendicular 45 to the carrier and an opposite surface to engage the yoke on the opposite side of said perpendicular position, said surfaces lying in the surface of a cylinder whose longitudinal axis coincides with the line of 50 pivoting of the yoke.

CHARLES F. CHAPMAN.
